UNITED STATES PATENT OFFICE.

SILAS H. HARDING, OF CHATHAM, MASSACHUSETTS.

FISH-WEIR.

SPECIFICATION forming part of Letters Patent No. 397,644, dated February 12, 1889.

Application filed December 17, 1888. Serial No. 293,828. (No model.)

To all whom it may concern:

Be it known that I, SILAS H. HARDING, of Chatham, in the county of Barnstable, State of Massachusetts, have invented a certain 5 new and useful Improvement in Fish-Weirs, of which the following is a description sufficiently full, clear, and exact to enable any person skilled in the art or science to which said invention appertains to make and use the same, 10 reference being had to the accompanying drawings, forming part of this specification, in which—

Figure 1 is a top plan view of my improved fish-weir; Fig. 2, an enlarged side elevation 15 of a section of the side nets in position; Fig. 3, an enlarged elevation of one of the stakes, showing the method of attaching the nets thereto; and Fig. 4, an enlarged top plan view of a portion of the latchet-rope and latches. 20 Like letters and figures of reference indicate corresponding parts in the different figures of the drawings.

My invention relates especially to that class 25 of fish-weirs which are particularly adapted for sea or salt-water fishing; and it consists in a novel arrangement of parts whereby a cheaper and more effective device of this character is produced than is now in ordinary use.

30 The nature and operation of the improvement will be readily understood by all conversant with such matters from the following explanation.

In the drawings, A represents the "bowl" 35 or "pound" of the weir, and B C the guides or runs. The bowl consists of a series of vertically-arranged stakes, b, driven into the ground in the form of a circle, the row of stakes at one side of the bowl running to 40 ward the center thereof, forming the mouth D, said stakes being of such length that their upper ends are above the water. The inner stakes, b', are a sufficient distance apart to permit a boat to pass between them into the 45 bowl. A side net, H, extends completely around the bowl and is secured by its upper edge to the tops of the stakes b. To the lower edge of the net are secured ropes d, (see Fig. 3,) which pass through openings in the lower 50 ends of the stakes and are fastened by a "half-hitch," f, or similar easily-detachable

manner, to the upper portion of said stakes. The bottom K of the bowl consists of a horizontally-arranged net divided into two sections, l m, the outer edges of said sections being secured in any suitable manner to the lower edge of the side net, H. Extending centrally from the mouth D along the bottom of the bowl and between the sections of net l m to a stake, b, directly opposite said mouth, 55 60 is the "backbone" or latchet-rope P. Secured to the back-bone P at suitable distances are loops or latches p, of small rope or line, (see Fig. 4,) and at corresponding distances in the adjacent edges of each section of the 65 bottom net, K, are fastened thimbles t, through which said latches may be threaded.

The guides or runs B consist of two series of stakes, b, provided with nets z, arranged in lines which converge toward each other, 70 forming a heart-shaped inclosure which opens at one end opposite the mouth D of the bowl.

The guides or runs C consist of a central row of stakes, g, provided with a net, i, on each side of which is disposed a diagonally-arranged series of stakes, j, provided with nets k, said runs opening into the end of the heart-shaped run opposite the mouth of the bowl.

The bowl-nets being arranged on the stakes 80 as described, the bottom nets are secured to the backbone P by threading each latchet through a thimble, t, and through the loop of the preceding latchet, as shown in Fig. 4, the end of the last latchet in the series being secured to the stakes b', where they can be 85 readily released.

In the use of my improvement the fish are driven into the runs C, and, seeking deep water, they follow the course of the nets 90 forming said runs, being thereby guided into the bowl A. In taking the fish from the bowl the lines d are released and each section of the bottom net dragged toward the edge of said bowl in a manner that will be readily 95 understood by all conversant with such matters without a more explicit description. The lines d are of such length that they will not be withdrawn from the openings in the bottom of the stakes when the nets are dragged.

As ordinarily constructed, the bottom nets of fish-weir bowls are formed in one piece.

Grass and other deposits rapidly accumulate on said nets, necessitating their frequent removal for the purpose of cleaning them. These deposits render the nets exceedingly heavy and difficult to handle. By dividing the nets and attaching them as in my improvement the nets are much more easily manipulated, as well as being less expensive to construct.

10 Having thus explained my invention, what I claim is—

1. In a fish-weir, a bowl comprising a side net secured to the weir-stakes and a bottom net secured to said side net, said bottom net being in two sections, adjacent edges of which are detachably secured to a centrally-arranged latchet-rope, substantially as described.
2. In a fish-weir, the bowl A, comprising the side net, H, secured by its upper edge to weir-stakes b, its lower edge being detachably secured to said stakes by lines d, passing

through openings in the lower ends thereof, and a bottom net, K, secured to said side net and formed in two sections, adjacent edges of said sections being detachably secured to a ²⁵ rope, P, by latchets p, substantially as set forth.

3. In a fish-weir, the combination of the side net, H, secured to stakes b, and provided with lines d, running in eyes in the lower ends of said stakes, the bottom net, K, constructed in sections l m, and secured to the lower edge of said side net, the centrally-arranged latchet-rope P, provided with latchets p, and the thimbles t, disposed in adjacent edges of said net-sections, all being arranged to operate substantially as described.

SILAS H. HARDING.
